UNITED STATES PATENT OFFICE

MAURICE GOUDARD, OF NEUILLY SUR SEINE, FRANCE

CARBURETOR

Application filed August 21, 1925, Serial No. 51,649, and in Belgium June 6, 1925.

This invention relates to carburetors of the type comprising a fuel overflow chamber or its equivalent and one or more nozzles and more particularly to a carburetor in which, during operation, variations are produced between the level of the fuel in the fuel overflow chamber or its equivalent on the one hand, and the orifice or orifices of the nozzle or nozzles on the other hand.

10 The improvements according to the invention are designed with the object of producing carburetors of the class in question which are adapted to function in a more practical manner than has hitherto been the case.

15 A carburetor constructed according to the invention is provided with at least one nozzle opening into the mixing chamber at the same level as the normal level of the liquid fuel in the overflow chamber or its equivalent, and 20 includes means for automatically producing at any desired time a variation in the level of the fuel in the overflow chamber in such a way that the fuel will flow freely through the nozzle opening even if it is not exposed 25 to the suction of the engine.

The invention also includes further constructional details which may be utilized in conjunction with the aforementioned principal arrangement or separately.

30 According to the invention, the means for varying the relative heights of the nozzle opening and of the liquid is controlled as a function of the variations of the position of the throttle, so that the most efficient carburation may be automatically ensured, and so that, in the case of carburetors having a plurality of nozzles the supply of fuel may take place under satisfactory conditions during the periods between which one of the nozzles goes into or out of operation.

35 Means are provided for instantly raising the level of the fuel with respect to the nozzle opening, where a sudden acceleration or speeding up is required.

40 The invention further includes various other constructional details and arrangements which will be more fully described hereafter.

45 In order that the invention may be clearly understood, it will now be explained with 50 reference to the accompanying drawings, but

it is to be observed that the description and drawings are given merely by way of example.

Figure 1 is a vertical central sectional view through the present carburetor, and

55 Figure 2 is an enlarged detail sectional view of the means for extending the height of the constant level chamber.

Referring to Fig. 1, the carburetor comprises in the ordinary way a principal nozzle *a* opening into the mixing chamber *b* of the engine, below the throttle *c*. In the present invention, fuel is admitted from a conduit *j* communicating through the interior of the apparatus with a vertical tube *j'*, the upper edge of which tube is at a height at which the level of the fuel is to be maintained under normal conditions. The fuel passing up the tube *j'* overflows into the chamber *d* and returns through a pipe *k* to the fuel reservoir. Between the inlet tube *j* and the tube *j'* is an obturating device, consisting of a needle *l*. This prevents the fuel from running from the reservoir up the passage *j* when the engine is stopped. *d⁰⁰* are channels 70 leading to the nozzle or nozzles, for instance to the principal nozzle *a* and to the slow speed nozzle *m*, in the construction shown.

A number of short axially aligned tubes, 80 of which two, *d²* and *d³* are shown, are mounted in the chamber *d* in such a way that the tube *d²* can be moved downwardly to seat its lower end upon the upper end of the tube *j'* to form an extension of the latter, and similarly that the tube *d³* can be moved downwardly to seat its lower end upon the upper end of the tube *d²* to form an extension of the latter in order to extend the height of the tube *j'* and thus control the hydrostatic pressure of the fluid supplied to the nozzle *a* and *m*.

85 The lower end of the tube *d²* is flared in order that it may fit over the upper end of the tube *j'*, and the lower end of the tube *d³* is similarly flared in order that it may fit over the upper end of the tube *d²*.

90 A tubular guiding member *d²⁰* has its lower end turned inwardly and secured to the tube *d²* and has its upper end extending above the upper end of the tube *d³*. Apertures 100

y and *z* formed in the tubular member d^{20} adjacent its bottom permit the escape from said member to the chamber d^0 of fuel overflowing from the upper end of the tube d^2 when the lower end of the latter is moved down over the upper end of the tube j^1 or from the upper end of the tube d^3 when the tubes d^2 and d^3 are both moved downwardly to seat their lower ends upon the upper ends of the tubes j^1 and d^2 , respectively. The tubes d^2 and d^3 may with advantage be operated from the throttle c , by mounting on the spindle of the said throttle a cam c' for operating a lever n fulcrumed on the carburetor casing. This lever in turn operates through the intervention of springs o , p , and q , the tubes d^2 and d^3 , the spring o being interposed between the lever n and a projecting portion on the tube d^3 , the spring p being mounted between the projecting portion on the tube d^3 and the bottom of the tubular member d^{20} , and the spring q being mounted between the bottom of the tubular member d^{20} and the bottom of the chamber d^0 . Moreover, the springs are so proportioned that, for a determined opening of the throttle c , the tubular member d^2 comes down upon the tube j^1 and adds to its length, this being an intermediate position of the throttle opening. In the neighbourhood of full opening of the throttle, the tubular member d^3 is added to the tube d^2 , thus securing an additional rise in the level of the fuel.

It may be desirable to provide the carburetor just described with means for automatically ensuring the opening and closing of the obturator or needle l . For this purpose said needle may be connected to a piston r slideable in a chamber d^{000} , in communication on one side with the atmosphere, and on the other with the mixing chamber above the throttle. The said piston is so interconnected with the obturator that when the engine is starting up or running at slow speed with the throttle closed, the suction of the engine upon the face of the piston in communication with the induction pipe above the throttle, causes the piston to rise and thus opens the obturator. The opening of the obturator is ensured, when the throttle is opened, by the action of the lever n on the piston r through a spring s .

In addition to the foregoing construction which gives excellent practical results, it may in some cases be desirable to adopt some or all of the following arrangements.

In the case of a carburetor with a plurality of nozzles means may be provided for regulating the height of the nozzle orifice with respect to the normal level of fuel in the reservoir.

For instance with the carburetor having a principal nozzle and a slow speed nozzle, the point at which they come into action

may be regulated by providing a cap adapted to screw on to the nozzle so as to regulate the height of the nozzle with respect to the level of fuel in the overflow chamber.

There may be combined with the nozzles a and m receptacles t and t' , adapted, respectively, to collect any fuel flowing from the corresponding nozzle. The bottom of the receptacle t is in connection with the mixing chamber above the throttle through a passage u . With this arrangement in starting up when the engine is cold, it is sufficient to produce, by hand, a momentary rise of the level of the fuel, by manipulating the throttle for instance, or, as shown at Fig. 1 by actuating a lever v of which one arm bears upon the upper end of the tubular member d^{20} .

The carburetor operates in the following way: As the throttle opens, cam e^1 actuates lever n , bringing pressure to bear on spring o and successively seating sections d^2 and d^3 , the fuel overflowing from the latter passing out through the apertures y and z of the tubular member d^{20} into the chamber d^0 and being drained off through overflow conduit k . The overflow from nozzle a is caught in basin t and is sucked up through bypass u at starting. If it be desired to provide an extra head of fuel at starting, lever v is actuated to depress section d^2 . The feed of fuel to chamber d^0 is under the control of valve stem l actuated by assembly s , r , d^{000} . At starting, the suction exerted in d^{000} , lifts piston r and permits fuel to pass into the nozzle and into chamber d^0 . During operation, piston r is lifted in the manner already described in another part of the specification.

What I claim and desire to secure by Letters Patent of the United States of America is:—

1. A carburetor including a chamber and fuel supply means including an overflow tube in said chamber, a mixing chamber, a throttle, a nozzle extending into the mixing chamber and connected to said overflow tube, and means operable by the movement of the throttle to extend the height of the overflow tube.

2. A carburetor including a throttle, a mixing chamber, a nozzle extending into said mixing chamber, means for controlling the hydrostatic pressure of fuel supplied to said nozzle, said means comprising a fuel chamber, sections in said fuel chamber communicating with said nozzle, and means operable by movement of the throttle for moving said sections into contact with one another.

3. The combination set forth in claim 2 including resilient means opposing the action of the throttle and tending to keep the sections separated from one another.

4. A carburetor including a throttle, a mixing chamber, a nozzle extending into said mixing chamber, overflow means comprising a plurality of sections and communicating

with said nozzle, and means for moving said sections successively into and out of contact with one another.

5. A carburetor including a chamber, overflow means in said chamber, a mixing chamber, a throttle, a nozzle connected to said overflow means and extending into the mixing chamber, and means for controlling the height of said overflow means comprising a plurality of superposed tubular sections, and springs for holding said sections separated, the springs being operated upon by the throttle to place the sections in continuity successively, said tubular sections being variously spaced, whereby the two lowermost sections engage first and the remaining ones in succession.

10. A carburetor including a chamber, overflow means in said chamber, a mixing chamber, a throttle, a nozzle connected to said overflow means and extending into the mixing chamber, and means for controlling the height of said overflow means comprising a plurality of superposed tubular sections, the lowermost section being fixed and the others movable and spaced from the lowermost and the one above, a plurality of springs, one to each movable section, for holding the movable sections spaced, and resilient means interposed between the throttle and the uppermost section, whereby as the upper spring is depressed by the throttle the other springs are depressed and the sections are successively placed into contact, the lowermost being the first to be contacted.

15. In testimony whereof I have hereunto set my hand.

MAURICE GOUDARD.
